UNITED STATES PATENT OFFICE

BRAUDDUS BROCK FORTNEY, OF LOUISVILLE, KENTUCKY

DESIGN FOR A COMBINED RADIO AND CLOCK CABINET

Application filed December 9, 1930. Serial No. 37,923. Term of patent 14 years.

To all whom it may concern:

Be it known that I, BRAUDDUS BROCK FORTNEY, a citizen of the United States, and a resident of Louisville, in the county of Jefferson and State of Kentucky, have invented a new, original, and ornamental Design for a Combined Radio and Clock Cabinet, as shown, of which the following is a specification, reference being had to the accompanying drawing, forming part hereof.

Figure 1 is a front elevation of a combined radio and clock cabinet showing my new design; and

Figure 2 is a side elevation of the same.

I claim:

The ornamental design for a combined radio and clock cabinet as shown.

BRAUDDUS BROCK FORTNEY.
